UNITED STATES PATENT OFFICE.

JOSEPH N. GOLDBACHER, OF NEW YORK, N. Y.

LEGGIN.

SPECIFICATION forming part of Letters Patent No. 295,538, dated March 25, 1884.

Application filed January 31, 1884. (No model.)

To all whom it may concern:

Be it known that I, JOSEPH N. GOLDBACHER, of the city, county, and State of New York, have invented a new and useful Improvement 5 in Leggins or Trouser-Protectors, of which the following is a full, complete, and exact specification, reference being had to the annexed drawings, which form a part thereof.

My invention relates to the construction of 10 a leggin or trousers-protector secured to the leg of the wearer by providing the longitudinal edges with ribs of rigid material broken or separated at certain intervals, and fastened to each other by any suitable means, the principal feature of the invention consisting in 15 supplying the leggin with adequate means for keeping it in position when on the leg, and in so arranging it that when not in use it can be folded up and placed in the pocket.

20 Figures 1 and 2 are plan views of leggins embodying the invention.

In the drawings, A indicates the leggin, and B B are the longitudinal edges of the same. Along these edges I fasten to the material of 25 the leggin the ribs, (indicated by C,) made of some rigid material, as whalebone, steel, or brass. These ribs C are separated from each other at certain intervals, (indicated by D,) and may be articulated, piece to piece, by any 30 suitable contrivance, as by hinged joint or links, as shown in Figs. 1 and 2. Through a fold along the upper edge of the leggin is passed an elastic string or band, (indicated by 35 M,) fastened at its two extremities to the upper ends, respectively, of the uppermost ribs C. The edges B B, supplied with the ribs C are brought together and held either by corresponding hooks and eyes fixed in the ribs C or by any other of the well-known and suitable 40 means for fastening. These ribs C may or may not be articulated to each other; but it will

be found advisable to hinge or link them together in some way to prevent their wearing through the material of the leggin and protruding, which would take place unless the 45 ribs are joined. In arranging the longitudinal edges of the leggin with separated ribs, and in providing them with suitable means of fastening, and with the elastic string M, I am enabled to produce a leggin which can be fastened 50 tightly on the leg of the wearer, and which will retain its position, whether worn over the pantaloons or otherwise, and when not in use can be folded up and placed in the pocket. In the use of the leggin as a trousers-protector from mud and dirt it will be 55 well to make the material of the leggin waterproof.

This invention may also be used to hold the gauntlet of a glove in position on the arm. 60

What I claim as new, and desire to secure by Letters Patent, is—

1. An improved leggin or trousers-protector provided along each of its longitudinal edges with ribs of rigid material broken or 65 separated at certain intervals, arranged substantially as set forth.

2. An improved leggin or trousers-protector provided along each of its longitudinal edges with ribs of rigid material broken or 70 separated at certain intervals and articulated to each other, substantially as described, and for the purpose set forth.

3. An improved leggin or trousers-protector provided with the elastic string M and 75 the ribs C, articulated to each other, arranged substantially in the manner described, and for the purpose set forth.

JOS. N. GOLDBACHER.
